(57) **CLAIM**

We claim the ornamental design for a vehicle wheel spoke brush, as shown and described.

DESCRIPTION

FIG. 1 is a perspective view of a vehicle wheel spoke brush embodying our new design;

FIG. 2 is a side elevation view thereof;

FIG. 3 is an opposite side elevation view thereof;

FIG. 4 is a top plan view thereof.

FIG. 5 is a front elevation view thereof; and,

FIG. 6 is a rear elevation view thereof.
